CLAIM

The ornamental design for a combined bottle and cap, as shown and described.

DESCRIPTION

FIG. 1 is a perspective view showing the design of the combined bottle and cap according to the invention;

FIG. 2 is an elevational view thereof, from one side, the view from the other side being the same;

FIG. 3 is an elevational view thereof from one end, the view from the other end being the same;

FIG. 4 is a top, plan view thereof;

FIG. 5 is a bottom plan view thereof, and,

FIG. 6 is an exploded perspective view thereof showing the cap separated from the bottle.

The portions of the bottle neck and the underside of the cap that are not shown in the drawings do not form part of the claimed design.
